(57) **CLAIM**

The ornamental design for a mobile device grip, as shown and described.

DESCRIPTION

FIG. 1 is a top right perspective view of a mobile device grip, according to the present invention.

FIG. 2 is a top left perspective view of the mobile device grip of FIG. 1;

FIG. 3 is a bottom left perspective view of the mobile device grip of FIG. 1;

FIG. 4 is a left side elevation view of the mobile device grip of FIG. 1;

FIG. 5 is a right side elevation view of the mobile device grip of FIG. 1;

FIG. 6 is a front elevation view of the mobile device grip of FIG. 1;

FIG. 7 is a back elevation view of the mobile device grip of FIG. 1;

FIG. 8 is a top plan view of the mobile device grip of FIG. 1;

FIG. 9 is a bottom plan view of the mobile device grip of FIG. 1; and,

FIG. 10 is a top front perspective view of the mobile device grip of FIG. 1.

Broken lines, where present, illustrate portions of the mobile device grip that form no part of the claimed design.
